UNITED STATES PATENT OFFICE.

VINCENT TERRANOVA, OF SAN FRANCISCO, CALIFORNIA.

FOLDING BED.

1,380,749.

Specification of Letters Patent. Patented June 7, 1921.

Application filed June 24, 1920. Serial No. 391,412.

To all whom it may concern:

Be it known that I, VINCENT TERRANOVA, a citizen of the United States, and a resident of the city and county of San Francisco, and 5 State of California, have invented a new and useful Folding Bed, of which the following is a specification.

My invention relates to beds adapted to be collapsed into a small space.

10 An object of the invention is to provide a bed frame which may be folded up into a small package, or opened out to form a bed.

The invention possesses other objects and 15 features of advantage, some of which, with the foregoing, will be set forth in the following description of the preferred form of my invention which is illustrated in the drawings accompanying and forming part 20 of the specification. It is understood that I do not limit myself to the showing made by the said drawings and description, as I may adopt variations of the preferred form within the scope of my invention as set 25 forth in the claims.

Referring to the drawings: Figure 1 is a plan view of the bed, a portion being broken away to disclose the structure. Fig. 2 is a perspective view of one end of the bed 30 frame. Fig. 3 is an elevation of the bed frame partially folded. Fig. 4 is a view showing the frame completely folded up.

My folding bed comprises a pair of end rails, each end rail being formed of pieces 2 35 and 3 pivotally connected by a knuckle joint 4. A reach rod connects the pivot pins 6 of the knuckle joints, and consists of center piece 7, end pieces 8 and intermediate pieces 9, all knuckle-jointed together so that the 40 reach rod is foldable as shown in Fig. 4.

Legs 11 are pivoted at the ends of the end rails and retained in the extended position by knuckle-jointed braces 12, interposed between the rail and leg. Similar braces 13 45 are interposed between the reach rod and end rails on both sides of the former. To permit the desired folding movement however, these braces are pivotally connected to end rail and reach rod for pivotal movement on each about two separate axes, that 50 is to say, for pivotal movement about a horizontal and a vertical axis.

After the bed frame is unfolded and set up, a fabric sheet 14, which may be of canvas or wire is stretched between the end rails. Preferably the fabric is fringed with

a number of coil springs 16 terminating in hooks adapted to be engaged through apertures 17 formed in the end rails. With the fabric top in place, a comfortable bed is 60 provided, especially suitable for automobile touring and camping use. The pull of the fabric prevents the folding of the reach rod, which is curved upwardly at the ends, so that the greater portion of it lies well below 65 the sag of the fabric top.

The end rails are preferably formed of angle section members as shown in Fig. 2 and the reach rod of channel section. If desired the frame may be formed of wood 70 suitably reinforced at the joints by metal fittings.

To fold the bed, the top is detached and the legs are turned in, then the end rails folded together. Fig. 3 shows the device at 75 this stage. The folded end rails inclosing the legs are then turned toward each other and inwardly, the reach rod folding about them as shown in Fig. 4. The detaching of the fabric top and the folding of the frame 80 occupy but a moment, and the setting up of the bed is equally simple and rapid.

I claim:

1. A folding bed comprising a pair of end rails, each end rail formed of two parts pivotally connected by a knuckle joint, and a reach rod formed of a plurality of parts pivotally connected by a knuckle joint connecting said end rails and pivoted in said end rail knuckle joints. 85 90

2. A folding bed comprising a pair of end rails formed of parts knuckle-jointed together, a reach rod formed of parts knuckle-jointed together for connecting said end rails, and braces pivoted to said reach rod 95 and to said end rails for pivotal movement on each about two separate axes.

3. A folding bed comprising a pair of end rails formed of parts knuckle-jointed together, a reach rod formed of parts knuckle-jointed together for connecting said end rails, and braces formed of parts knuckle-jointed together and pivoted to said reach rod and to said end rails for pivotal movement on each about separate axes. 100 105

4. A folding bed comprising a pair of end rails formed of parts knuckle-jointed together, a reach rod formed of parts knuckle-jointed together for connecting said end rails, braces formed of parts knuckle-jointed together and pivoted to said reach rod and to said end rails for pivotal move- 110

ment on each about separate axes, and a fabric sheet resiliently secured between said end rails.

5. A folding bed comprising a pair of end rails formed of parts knuckle-jointed together, a reach rod formed of parts knuckle-jointed together and connecting the pivot pins of said first named knuckle joints, fold-

ing legs on said end rails, folding braces interposed between said end rails and said 10 reach rod, and a fabric sheet resiliently mounted on said end rails.

In testimony whereof I have hereunto set my hand.

VINCENT TERRANOVA.
